UNITED STATES PATENT OFFICE

HENRY T. SCHIFF, OF CHICAGO, ILLINOIS

DESIGN FOR A LIGHTER FOR CIGARS, CIGARETTES AND THE LIKE

Application filed August 8, 1929. Serial No. 32,332. Term of patent 3½ years.

To all whom it may concern:

Be it known that I, HENRY T. SCHIFF, a citizen of the United States, residing at Chicago, in the county of Cook and State of Illinois, have invented a new, original, and ornamental Design for Lighters for Cigars, Cigarettes and the like, of which the following is a specification, reference being had to the accompanying drawing, forming a part thereof.

In the drawing,

Figure 1 is a side elevation of a lighter for cigars, cigarettes and the like, showing my new design.

I claim:

The ornamental design for a lighter for cigars, cigarettes and the like, as shown.

HENRY T. SCHIFF.
